MOVING PICTURE FILM REEL

Jacob M. Goldberg, Denver, Colo.

Application December 4, 1936, Serial No. 114,171

3 Claims. (Cl. 242—70)

This invention relates to improvements in reels and has reference in particular to a reel of the type employed for moving picture films.

In U. S. Letters Patent 2,051,334 granted to me on August 18, 1936, a film reel, constructed almost entirely from sheet metal formed by proper dies is shown. The present invention is in the nature of an improvement in the structure of the reel disclosed and claimed in the patent above identified.

It is the object of this invention to produce a film reel of substantial construction that can be formed almost entirely of sheet metal, drawn to the desired shape by dies.

Another object is to produce a reel in which the hub, is positively held from rotation in the reel and whose construction is such that it will withstand the severest strains to which it may be subjected in normal operation, without breaking loose from the reel or moving transversely thereof.

A further object is to produce a construction in which the hub is provided with a radial flange or plate secured to it in such a way that neither relative, rotary, longitudinal or wobble movement can take place.

A still further object of this invention is to produce a reel having a tubular elongated hub whose ends are engaged by the edges of openings in hub portions of the side members, in such a way that it is braced against accidental displacement from its perpendicular position and in which the hub portions of the side members also serve to prevent axial displacement of the hub.

The above and other objects that may become apparent as this description proceeds are attained by means of a construction and an arrangement of parts that will now be described in detail, and reference for this purpose will be had to the accompanying drawing in which the structure has been illustrated and in which:

Figure 1 is a side elevation of the reel, to a reduced scale;

Figure 2 is a section taken on line 2—2, Fig. 1, and shows the center portion of the reel to a scale approximately twice that used in Fig. 1;

Figure 3 is a view, partly a plan and partly a section, taken on line 3—3, Fig. 2;

Figure 4 is a side elevation of the hub member and the anchor plate that is attached to it;

Figure 5 is a fragmentary section showing a modified construction; and

Figure 6 shows a slight modification.

The reel comprises two side members 6 that are identical in size and shape. It is not essential

that they shall be identical, but it is preferable because both can then be formed by a single die. The sides have offset circular areas 7 that are connected to them by substantially cylindrical walls 8. From Fig. 2 it will be observed that the center portions 7 are surrounded by beads or ridges 9 which abut when the reel is assembled, in the manner shown in Fig. 2. The beads are not, however, essential to this invention.

The offset areas or portions 7 are provided with a plurality of holes 10, six being shown. These holes are formed in a circular row by the dies and alternate holes are punched out full size, while the others are drawn so as to leave a cylindrical flange like that indicated by dotted lines in Fig. 2 and designated by numeral 11. The tubular flanges are in the nature of tubular rivets and are employed to hold the parts in assembled relation, as will hereinafter be pointed out. The offset portions 7 may each have an integral hub portion 13, provided with a central opening 14, surrounded by an inwardly directed flange 15, whose function will appear as the description proceeds.

A metal plate 16 is positioned in the space between the opposed or adjacent surfaces of the offset portions 7 and this plate is provided with openings of the proper size to receive the tubular flanges 11, which in the assembled reel, are flanged outwardly in the manner common with tubular rivets and the flanges 17 serve to secure the sides and the plate 16 together as a unitary assembly. The thickness of plate 16 is such that it will fill the space between the offset portions when the beads 9 are in contact, as shown in Fig. 2. If the construction illustrated in Fig. 6 is employed, the thickness of the plate and the extent of the offset must be so calculated that the distance between the inner surfaces of the sides will be sufficient to receive the film. It is evident that the plate 16, when the parts are assembled, will be positively held against rotation, and when the plate is made from steel, it will impart great strength and rigidity to the center portion of the reel.

Plate 16 is provided with a central opening of any suitable shape, either round, polygonal or oblong and the center of this opening must coincide with the center of the cylindrical walls 8 and 13. The center opening in plate 16 is formed by dies in such a way as to leave a flange 18 that engages the outer surface of an elongated tubular hub member 19, whose size and shape is such that it will fit the opening with a snug driving fit. Since the flange 18 is formed by dies, the

side of this flange can be formed perpendicular with the plane of the plate, and therefore the hub member 19 will be positioned with its axis perpendicular to the plate. If the hub member 5 19 has a circular cross section, it is preferably welded to the flange 18.

When a square or non-circular hub member is employed, the ends are made circular, as indicated at 20, whereby shoulders 21 are formed 10 against which the flanges 15 rest; this serves to brace the hub member and to hold it from moving longitudinally in the opening in the plate.

In Fig. 5, a slightly modified construction is shown in which the hub portions 13a are made 15 separate from the offset portions 7' and provided with flanges 22 that are overlapped by the edges of parts 7'.

Plate 16 serves as an anchor for the hub member 19 and positively prevents it from turning 20 relative to the reel. Flange 18 serves to hold hub member 19 with its axis perpendicular to the plane of plate 5, and this action is further assisted by the action of the hub portions 13 and 13a.

The sides 6 are provided with the usual openings 25 23 and have strengthening ribs 24.

The circular surfaces 7, 7' and 7'' are offset to an extent that is substantially equal to one-half the width of the film, minus one-half the thickness of plate 16 so that when the parts are assembled, the distance between the sides of the reel will be proper to accommodate the film. When the construction illustrated in Fig. 2 is employed, the beads 9 extend beyond the inner surface of the circular portion 7 a distance equal to one-half the thickness of plate 16, as hereinbefore described.

Reels constructed in accordance with this invention can be formed from sheet metal, with the exception of the hub member 19, and it is 40 also practical to form this from sheet metal formed into a tube. Due to the fact that plate 16 is quite rigid and is firmly attached to the hub 19, the reel will remain true and will successfully resist forces that tend to make it wobble.

45 Although the parts have been shown as connected by tubular members 11, it is permissible to replace these by rivets or by electro welding.

Having described the invention what is claimed as new is:

50 1. A moving picture film reel comprising two

substantially identical circular side members, each having a central circular area, offset from the plane thereof a distance slightly less than one-half the width of a film, a metal plate positioned between the adjacent surfaces of the offset areas, 5 the plate having a central opening surrounded, on one side of the plate, by a flange, means for interconnecting the sides and the plate to form a unitary assembly, a tubular, elongated hub extending through the opening in the plate, with its outer surface in engagement with the inner surface of the flange, means holding the plate and hub from relative movement, and means connected with the side members embracing the ends of the hub for effecting a bracing action 15 between the hub and the reel.

2. A moving picture film reel comprising two substantially identical, circular side members, each having a central annular area, offset from the plane thereof a distance slightly less than 20 one-half the width of a film, the offset area being connected with the sides by a substantially cylindrical wall slightly wider than the offset distance of the offset area whereby a circular ridge is formed about the latter, that serves to space adjacent surfaces of the offset areas, a plate in the space between the offset areas, means for interconnecting the sides and plate to form a unitary assembly, the plate having a central opening, a 30 tubular hub extending through the opening, the axis of the hub being perpendicular to the plane of the plate, and means for effecting a non-rotatable connection between the hub and plate.

3. A moving picture film reel comprising in combination, two substantially identical circular 35 side members, each having a circular area, offset from the plane thereof a distance slightly less than one-half the width of a film, a metal plate positioned between the adjacent surfaces of the offset areas, the plate having an opening means 40 for interconnecting the sides and the plate to form a unitary assembly, a tubular, elongated hub extending through the opening in the plate with its outer surface in engagement with the side of the opening, means holding the plate and 45 hub from relative rotary movement, and means connected with the side members, embracing the ends of the hub for effecting a bracing action between the hub and the reel.
